UNITED STATES PATENT OFFICE.

RUDOLPH M. HUNTER, OF PHILADELPHIA, PENNSYLVANIA, ASSIGNOR TO PATTERSON-
ALLEN ENGINEERING COMPANY, A CORPORATION OF NEW YORK.

PIPE-FLANGING MACHINE.

1,039,948.

Specification of Letters Patent. Patented Oct. 1, 1912.

Application filed February 3, 1912. Serial No. 675,826.

To all whom it may concern:

Be it known that I, RUDOLPH M. HUNTER, a citizen of the United States, and resident of Philadelphia, county of Philadelphia, 5 State of Pennsylvania, have invented an Improvement in Pipe-Flanging Machines, of which the following is a specification.

My invention has reference to machines for attaching flanges to pipe and consists of 10 certain improvements which are fully set forth in the following specification and shown in the accompanying drawings which form a part thereof.

The object of my invention is to provide a 15 suitable construction of machine for expanding the ends of pipe into flanges whereby a firm and tight union is made between the two, and more specifically, my object is to accomplish this result by means of expanding dies operated by hydraulic pressure 20 without requiring a rigid abutment against which the dies are supported and held.

My invention consists in a suitable means for positioning a pipe flange combined with 25 an annular sectional expanding die having a conical aperture and a conical mandrel or arbor extending through the annular die for expanding the same, power devices, preferably hydraulic, for simultaneously applying pressure to the annular die and the arbor in opposite directions, whereby the die is expanded; further, in means for providing a slight excess of pressure upon the annular die over that applied to the conical mandrel 30 or arbor for positioning the die upon the work at the moment of expanding the die; further, in the means above specified when so constructed that the annular die and mandrel may be moved together longitudinally 35 within the pipe.

My invention also comprehends details of construction which, together with the features above specified, will be better understood by reference to the drawings, in 40 which:—

Figure 1 is a sectional elevation of a pipe flanging machine embodying my improvements; Fig. 2 is a front elevation of the same; Fig. 3 is a sectional elevation on line 50 *---a* of Fig. 1; Fig. 4 is an end elevation of the annular sectional die; and Fig. 5 is an elevation of the means for operating the clamps removed from the machine.

2 is the main frame of the machine and is provided with a housing 3 of annular form

in which is journaled the clamp adjusting frame 7 having the spiral teeth as shown in Fig. 5. This frame 7 may be rotated in the housing by means of the hand wheel 9.

5 are a series of radial clamping arms 60 guided upon the housing and positioned by the annular cap plate 4 bolted to the housing. The teeth of these clamping arms 5 engage the spiral teeth of the annular frame 7. The inner ends of the clamping arms 5 65 are provided with notched portions 6, constituting jaws for receiving and positioning the pipe flange 10 within which the end of the pipe 11 is inserted. By rotating the hand wheel 9, the clamping arms 5 may be 70 moved outward or inward to support and clamp pipe flanges of various sizes.

18 is a hydraulic cylinder and is bolted to the main frame 2 with its central line axially positioned with respect to the clamping devices for clamping the pipe flange. This cylinder is of uniform diameter excepting at its rear end 31 in which it is of somewhat smaller diameter. A piston 19 of 75 trunk form works through the portion 31 of smaller diameter of the cylinder and is provided with a piston portion 20 fitting the larger diameter of the cylinder 18. 21 is a head which is clamped to the end of the trunk piston 19 to limit the forward motion 80 of the piston within the cylinder. This piston 19 is provided with a shaft 16 upon the end of which is arranged the conical mandrel or arbor 15. Fitting into the other end of the cylinder 18 is a plunger 25, said plunger 85 sliding upon the shaft 16 and forming a liquid tight joint therewith by means of the packing 27. The cylinder 18 is also packed at 26 about the plunger 25 to prevent the escape of the hydraulic fluid. This plunger 25 is extended toward the arbor or mandrel and terminates in a flange face 17.

Surrounding the mandrel 15 is the annular sectional die 12 which is composed of 90 segments held in annular arrangement by means of suitable springs 14. This annular die is also provided with ribbed portions 13 and the radial flange portions 12^a. The annular die 12 is held in position against the flange 10 by the flange face 17 of the plunger 25, so as to position the die within the end of the pipe and its flange. When the mandrel 15 is moved within the die 12, the sections of the latter are expanded outward and the rib 13 of said sections forces 95 100 105 110

the pipe outward into the annular groove of the usual pipe flange.

It will be observed that the diameter of the piston portion 20 which is connected with the mandrel 15 by the shaft 16 is the same diameter as the plunger 25 which operates upon the annular die 12, so that if pressure fluid is admitted alone between these two parts by the pipe 28 and valve 29, there will be an equal pressure upon the annular die 12 which will allow it to expand without material tendency to displace it in the direction of the axis of the mandrel. It will be further seen that, if water pressure is admitted by valve 23, whatever difference in pressure may exist between the plungers 20 and 25 by reason of the fact that the plunger 19 is of slightly less diameter than the piston 20 and the water about it is made to reduce the available power of the piston 20 in moving away from plunger 25, there will be a slightly greater pressure by the face 17 upon the die 12 and in a direction against the work 10 than will occur by the action of the arbor 15 in its action upon the die in the opposite direction or away from the work. In this way, there will be just enough pressure upon the die 12 to hold it to the flange or work 10 which is held by the jaws 6 of the clamping arms 5, said jaws being so formed that they retain the flange in proper position and take up the slight thrust due to the differences in the plunger 25 and the trunk piston 19 and their action upon the die and arbor. When it is desired to remove the pressure from between the plunger 25 and piston 20, the turning of the valve 29 will allow the escape of the water through the discharge pipe 30. A pipe 22 and a valve 23 are also provided for admitting water under pressure to the cylinder around the trunk piston and between the piston 20 and the outer end of the cylinder through which the trunk piston 19 passes, and the water may be allowed to discharge from the cylinder through the discharge pipe 24 by proper manipulation of the valve 23. It is also pointed out that while the shaft 16 is rigidly secured and moves positively with the trunk piston 19 and piston 20, the said shaft is formed of two diameters, namely, a smaller diameter 34 where it passes through the inner end of the plunger 25, and a larger diameter 35 where it passes through a stuffing box 27 at the outer end of the plunger 25. It will further be seen that this plunger is hollow to provide a water space from which is extended a port 33 of elongated form along the surface of the plunger. This port is in communication with a port 32 in the cylinder 18, and said port 32 at its other end opens through the inner wall of the cylinder into the space about the trunk piston 19.

65 Considering now the operation of the ma-

chine and assuming that the machine has just completed the expanding of a pipe into a pipe flange and moved the conical arbor to the right, as shown, the valve 29 turned to discharge the water from the cylinder 18 into the discharge pipe 30 and the valve 23 already turned to permit water from the pipe 22 to pass into the cylinder 18 around the trunk piston 19. As this piston 19 cannot move farther to the right (Fig. 1), it is evident that the water will flow through the ports 32 and 33 into the space within the plunger 25, and acting upon the greater area on the inside of this plunger surrounding the smaller cross section 34 of the shaft 16, it moves the plunger 25 to the left so as to remove the pressure of the flange face 17 from the annular die 12, allowing it to move to the left. When the pressure of flange 17 on the die is removed, the valve 23 is closed. By turning the hand wheel 9, the jaws 6 will be moved away from the flange 10 and the pipe with its attached flange may be removed. Assuming now, that the machine is in this condition last described, a new flange is inserted in place and clamped by the clamping jaws 6. A pipe end 11 is then thrust through the flange and against the annular die 12. Valve 29 is then turned to supply water under pressure to the cylinder between the plunger 25 and the piston 20. The effect of this pressure is to force the plunger and piston in opposite directions, but as the area of the plunger 25 is greater than the available area of the piston 20 and trunk piston 19, it is evident that the plunger 25 will first move outward and push the annular die 12 up to the position shown against the work, namely, the pipe flange 10 and the end of the pipe 11, and immediately thereafter, there will be a movement of the piston 20 and the trunk piston 19 together with its shaft 16 and the arbor 15, said movement being to the left of Fig. 1 and with the result of expanding the pipe into the groove of the flange. While we have here approximately the full power equal to that of the trunk piston 19 to expand the die in the performance of its work of securing the tube to the flange, only a small amount of power is utilized for holding the dies to their position upon the work and without the necessity of special means for directly holding the die itself. The apparent difference in diameters of the plunger 25 and the trunk piston 19 is greater than that which is effective in holding the die in position upon the work, because of the fact that there is a certain portion of the area of the plunger 25 made non effective owing to the employment of the shaft 16 extending through it, aside from the two diameters 34 and 35 of the said shaft 16 extending through this plunger and into the water space within the same in which the

full pressure may be maintained. It is pointed out that wherever these plungers 20 and 25 may be at the beginning of the expanding operation, the force of the pressure from valve 29 will produce the expansion without disturbing the position of the dies and will not put any additional pressure by the flange 17 upon the die and work. While the pressure from pipe 22 may be applied constantly during the operation of the machine for insuring the pressure by the flange 17 upon the die and work and for releasing this pressure at the completion of the expanding operation, the operator may, if he so desires, turn the valve 23 to cut off this pressure during the period of expanding, because there will be no tendency to displace the die relative to the work and especially not after the die has taken hold on the work. It will now be understood that the work of expanding the die having been accomplished, it is only necessary to turn the valve 29 to permit the discharge of the water from the cylinder between the plunger 25 and the piston 20 into the discharge pipe 30 to enable the pressure of the water in the cylinder around the trunk piston 19 to move the piston 20 together with its shaft 16 and arbor 15 to the right for relieving the annular die of expanding pressure. The position of the parts shown in Fig. 1 will then have been accomplished. Aside from this act of releasing the annular die from the pipe, the water flowing through the ports 32 and 33 into the interior of the plunger 25 will cause the said plunger to move slightly backward to the left relatively to the shaft 16 to relieve pressure upon the die 12. The edges 6 may be moved away from the flange 10 and the pipe with the flange withdrawn from the die. It will be noticed that the port 32 where it opens into the cylinder around the trunk piston 19 is such that it would be closed by the piston 20 upon the beginning of the expanding operation of the die 12, and this is made so to remove the action of the water pressure within the plunger 25 during the expanding operation, this port 32 being uncovered only when the arbor has been forced out of the annular die to the position indicated in the drawing, at which time the pressure upon the plunger 25 from the water supply within its hollow center is required to be made effective in moving the plunger inward upon the cylinder as a final operation of relieving all pressure upon the annular die itself. Where this port 32 is closed by the piston 20, any slight increase in pressure within the chamber of the plunger 25 due to the shifting of said plunger upon the part 34 of the shaft 16, would be neutralized owing to the fact that there is no packing about the said part 34. This arrangement of the port 32 whereby it is automatically closed by the piston 20 may be omitted, if so desired, so that the water pressure within the plunger 25 is maintained at all times. At no time is the port 32 uncovered by piston 20 to provide communication with the space between the pistons 20 and 25.

I have described the operation of the machine with the full water pressure supplied constantly to the cylinder around the trunk piston 19, and the manipulation of the apparatus accomplished wholly by the adjustment of the valve 29, this of course assuming that the pressures in the two pipes 22 and 28 are the same, but it is evident that the valve 23 may be manipulated, if so desired, so as to relieve the water pressure from around the trunk piston 19 whenever the water is delivered to the cylinder between the piston 20 and the plunger 25, and vice versa, as the only time that the active pressure from the pipe 22 is required is after the expanding operation when relieving the mandrel from the die and for moving the plunger 25 to remove the pressure of the face 17 from the die. The operation of my improved machine may be varied by still further manipulations at the option of the operator: For example, assuming that the parts were as in Fig. 1 with the conical arbor 15 just moved to the right and the plunger 25 just about to be moved to the left to relieve pressure of the flange upon the die 12, and that as soon as the pressure by the flange upon the die 12 has been relieved, the valve 29 is closed from discharging through pipe 30, we will then have a solid body of water between the plunger 25 and piston 20, and also a solid body of water around the trunk piston 19 and with full pressure from pipe 22. Assuming also, that the pressure in the pipe 22 is only sufficient to apply to the flange 17 the amount of pressure required to hold it to the dies and work without straining the work and for returning the plunger 25 when removing the flange 17 from the die 12, it will then be understood that, with this lesser pressure constantly exerting itself around the trunk plunger 19 and intermittently exerting itself within the plunger 25 against the inner face thereof in opposition to the shoulder between the parts 34 and 35, if the higher pressure of water from the pipe 28 be turned on, the effect will be to move the plunger 25 against the lesser pressure until the flange 17 comes against the die and presses it up to the work, and thereafter this excessive pressure between the plunger 25 and piston 20 will cause the piston to move to the left with the expanding operation of the dies taking place. To return the parts to their original position, it will only be necessary to turn the valve 29 to discharge to the pipe 30, in which case, the piston 20 will move to the

right until the port 32 is uncovered, and then the plunger 25 will move slightly to the left to relieve the dies; the valve 29 is then closed and the pipe, with its attached flange, may be removed. In this operation, the water pressure in pipe 22 may be maintained by any of the ordinary accumulators and maintained from the source of higher pressure to the pipe 28, such means being well known in hydraulic engineering and forming no specific part of my invention.

The characteristic feature of this hydraulic pipe flanging machine is, that providing a holder for positioning the work, the dies are brought into position upon the work and positioned thereby by the work in an automatic manner without putting any material strain upon the work other than expanding the metal thereof, the excessive strain applied between the mandrel and the annular die being expended for the purpose of expanding the tube within the flange without material tendency to displace the die upon the work. The excess of pressure on the flange 17 to hold the die up to the work may be anything which the designer wishes, and may be varied by varying the sizes of the areas of the pistons and plungers, or by varying the extent of pressure by pipe 22 relatively to pressure in pipe 28, so that only the minimum pressure need be put upon the work in positioning the dies. The applicant is certainly not restricting himself to exact proportions nor to exact pressure, as those are liberties which the user of the invention may employ in adapting it to the particular work required. These points would naturally vary according to the size of the machine and frictional resistance of its parts, but the principles of operation would remain the same. It is evident that this characteristic feature may be accomplished by various modifications of the character of machine herein set out, and I therefore do not restrict myself to the details of construction herein described, as my invention will comprehend all modifications of the machine which will accomplish these specific results and which may come within the scope of the claims.

Having now described my invention, what I claim as new and desire to secure by Letters Patent, is:—

1. In a pipe flanging machine, the combination of a holder for the pipe flange, an expanding annular die, a tapered arbor for expanding the die, a hydraulic cylinder, a plunger within the hydraulic cylinder for applying pressure to the annular die in one direction, a piston or plunger for moving the tapered arbor in the opposite direction, means for supplying fluid under pressure between the two plungers or allowing of its escape when necessary, and means by which the direction of movement of the plunger or

piston and the tapered arbor may be reversed when the pressure is relieved between the two plungers.

2. In a pipe flanging machine, the combination of a holder for the pipe flange, an expanding annular die, a tapered arbor for expanding the die, a hydraulic cylinder, a plunger within the hydraulic cylinder for applying pressure to the annular die in one direction, a piston or plunger for moving the tapered arbor in the opposite direction, means for supplying fluid under pressure between the two plungers or allowing of its escape when necessary, means by which the direction of movement of the plunger or piston and the tapered arbor may be reversed when the pressure is relieved between the two plungers and when the plunger for applying pressure to the annular die is stationary, and means by which the direction of movement of said last mentioned plunger may be finally reversed to remove the pressure thereof from the annular die.

3. In a pipe flanging machine, the combination of a holder for the pipe flange, an expanding annular die, a tapered arbor for expanding the die, a hydraulic cylinder, a plunger within the hydraulic cylinder for applying pressure to the annular die in one direction, a piston or plunger for moving the tapered arbor in the opposite direction, means for supplying fluid under pressure between the two plungers or allowing of its escape when necessary, means by which the direction of movement of the plunger or piston and the tapered arbor may be reversed when the pressure is relieved between the two plungers and when the plunger for applying pressure to the annular die is stationary, and means by which the direction of movement of said last mentioned plunger may be finally reversed to remove the pressure thereof from the annular die the time of said action being controlled by the first mentioned plunger or piston which operates the tapered arbor whereby after the expanding operation the tapered arbor is first moved backward to allow the annular die to collapse and then the pressure upon the annular die which holds it to the work is relieved.

4. In a pipe flanging machine, the combination of means for holding a pipe flange, with an annular expanding die formed of sections having a laterally projecting flange to rest against the pipe flange, a tapered arbor extending through the annular expanding die for expanding it, and separate power applying means for simultaneously applying pressure upon the annular expanding die and the tapered arbor in opposite directions, whereby said die may be expanded within the work without necessity for any other support but the work and the power applying devices.

5. In a pipe flanging machine, the combination of means for holding a pipe flange, with an annular expanding die formed of sections having a laterally projecting flange 5 to rest against the pipe flange, a tapered arbor extending through the annular expanding die for expanding it, and separate power applying means for simultaneously applying pressure upon the annular expanding die and the tapered arbor in opposite directions but in which the power applying devices acting upon the annular die apply a pressure in one direction slightly in excess of the pressure applied upon the 10 tapered mandrel in the opposite direction to position the die upon the flange constituting the work during the expanding operation, whereby said die may be expanded within the work without necessity for any other 15 support than the work and the power applying devices.
6. In a pipe flanging machine, the combination of means for holding a pipe flange, with an annular expanding die formed of sections having laterally projecting flanges 20 to rest against the pipe flange, a tapered arbor extending through the annular expanding die for expanding it, a cylinder, a plunger in said cylinder having an extension resting upon the annular expanding die, a second plunger arranged in the cylinder and having an extension connecting with the tapered arbor, and means for controlling the admission of a fluid to and its 25 discharge from the cylinder between the plungers.
7. In a pipe flanging machine, the combination of means for holding a pipe flange, with an annular expanding die formed of sections having laterally projecting flanges to rest against the pipe flange, a tapered arbor extending through the annular expanding die for expanding it, a cylinder, a plunger in said cylinder having an extension 30 resting upon the annular expanding die, a second plunger arranged in the cylinder and having an extension connecting with the tapered arbor, means for controlling the admission of a fluid to and its discharge from the cylinder between the 35 plungers.
8. In a pipe flanging machine, the combination of means for holding a pipe flange, with an annular expanding die formed of sections having laterally projecting flanges to rest against the pipe flange, a tapered arbor extending through the annular expanding die for expanding it, a cylinder, a plunger in said cylinder having an extension resting upon the annular expanding die, a second plunger arranged in the cylinder and having an extension connecting with the tapered arbor, means for controlling the admission of a fluid to and its discharge from the cylinder between the plungers, and means controlling a fluid for positively moving the plungers toward each other for removing pressure upon the annular die.
9. In a pipe flanging machine, a flange holder consisting of an annular housing with radially movable jaws guided therein and a rotatable frame having spiral teeth engaging the radially movable jaws to simultaneously move them radially, combined with an annular die arranged within the housing and centrally in respect to the radially movable jaws, a tapered arbor for expanding said die, and power devices for simultaneously applying pressure upon the annular die and the tapered arbor in respectively opposite directions.
10. In a pipe flanging machine, means for holding the pipe flange, an annular expanding die for expanding the pipe within the flange, a tapered arbor extending through the annular die for expanding it, and simultaneously acting power devices for holding the annular die against the work with slight positioning pressure when applying great pressure upon the annular die and tapered arbor in opposite directions, whereby the dies may be positioned by the work and the expanding operation performed upon said work without applying excessive displacing strain thereto.

In testimony of which invention, I hereunto set my hand.
